COLLINS K. ORTON, OF SAN FRANCISCO, CALIFORNIA.

CUTTER-HEAD.

1,112,085.

Specification of Letters Patent. Patented Sept. 29, 1914.

Application filed February 11, 1914. Serial No. 818,952.

To all whom it may concern:

Be it known that I, COLLINS K. ORTON, a citizen of the United States, residing in the city and county of San Francisco and State of California, have invented new and useful Improvements in Cutter-Heads, of which the following is a specification.

My invention relates to improvements which are especially designed for rotary cutter heads, such as are used in planers and like machines.

The object of the present invention is to provide a simpler and more effective means for securing the cutter blades in place in the cutter head or body.

It consists in an improved method for locking the cutter blade in position, in operating the locking mechanism, and in details of construction which will be more fully explained by reference to the accompanying drawings, in which—

Figure 1 is a transverse sectional view of a cutter head taken through the plane of the securing device. Fig. 2 is a similar view showing a slight modification. Fig. 3 is an end view of a locking wedge. Fig. 4 is a side elevation of same.

For the purpose of securing the cutters of planer and like heads in position, various devices have been employed to prevent the cutter from moving from its position when once established. In my device the planer head or cylinder A has formed in it a sufficient number of channels 2 made longitudinally along the periphery of the head and parallel with each other. These channels are formed with a deeper portion 2^a, adapted to receive the cutter blade 4; the back wall of each of said channels being tangential to a circle made interior to the outer periphery of the cutter head, and these backs serve as a support for the back of the cutter knife. The opposite side or front of the channel 2 is substantially radial with the axis of the cutter head, and the back and front sides thus converge from the interior outwardly.

In order to lock the knife in position, I have shown a block 5 having a substantially trapezoidal shape; that is, the back of the block is a plane which abuts against the front of the cutter blade and the opposite side of the block is a plane which coincides with and fits the front plane of the channel 2. The top of this block, corresponding with the periphery of the cutter head, is made concave, as shown at 6, so as to form an

effective gullet for any chips detached by the operation of the cutter, this surface being unperforated.

The inner face of the block may be made in two ways. As shown in Fig. 1 it has a screw threaded recess 7 bored into it radially, said recess stopping short of the upper surface. Coincident with and fitting this recess is a threaded screw 8, having a gear 9 fixed to the inner end. This gear is contained in the bottom of the channel 2, having its axis radial with that of the screw 8, and its periphery may project slightly beyond the face into an undercut space below the bottom of the front face of the channel 2, as shown.

A hole 10 is drilled into the periphery of the cutter head in such a position that it intersects that part of the channel in which the gear lies. A key 11 has pinion teeth formed upon its lower end, and this key, fitting the opening 10, may be introduced so that its teeth will engage those of the gear, thus enabling the gear to be turned with whatever power may be necessary.

The trapezoidal block and the blade being introduced into the channel in proper position, with the inclined rear of the block pressing against the front of the blade, and the blade itself contacting with the back of the channel of the cutter head, the key 11 may be introduced to engage with the gear wheel carrying the screw, the latter having been previously introduced into the space beneath the block. By turning the key, the screw will be revolved and the threads of the screw will advance the block in its angular channel until its face is locked firmly against the blade of the cutter to render the latter immovable. The inner surface of the channel in this construction has a cone-shaped socket 12 made in it in line with the axis of the gear and the screw stem, and the lower part of the gear is formed in the same manner to fit this socket, which thus serves as a thrust bearing for the gear and screw so that the latter may exert its full force upon the block.

In Fig. 2 the arrangement of all of the parts is similar, except that the block has the cone-shaped socket in it. The screw threaded chamber is made in line with this bearing, and the screw, which enters the screw threaded socket, extends inwardly into the body of the cutter head. The gear and the pinion key are constructed similar to that previously described, the only differ-

ence being that the position of the screw is reversed to enter the cutter head instead of the block, the action being in all respects similar. The block is thus made solid and 5 no supplemental block or part is necessary between it and the cutter blade, the contact between the two being direct.

It is manifest that the locking block may 10 be made the full length of the cutter head, or a plurality of such blocks may be fixed at intervals from one end to the other of the cutter head by being locked independently.

While the cutter blades are shown as being 15 positioned tangential to a circle made interior to the outer periphery of the cutter head, it is obvious that they may be positioned radially or angularly. The position of the cutters may in other words be changed to suit conditions and the material treated.

20 I also wish it understood that various other changes in form, proportions and minor details of construction may be resorted to within the scope of the appended claims and that I do not wish to limit myself to the 25 specific design and construction here shown.

Having thus described my invention, what I claim and desire to secure by Letters Patent is—

30 1. In combination with a cutter head having a channel, a block in the channel, one of said parts having an annular recess with a central threaded hole leading therein, the

other part having a socket, and the head having a hole which intersects the recess, a 35 screw threaded into said threaded hole, a gear between the block base and the channel bottom affixed to said screw and being rotatably received in said annular recess, said gear having a journal which projects into the socket and having a part thereof projecting into said hole which intersects the recess, and a key having pinion teeth insertible in said last named hole and having its teeth engageable with the teeth of said gear. 40

2. In combination with a cutter head having a channel in its periphery, and a block in the channel, a gear disposed between the block base and the bottom of the channel and having a journal which bears on one of 50 said elements, a screw connected to the gear and rotatably and positively engaged with the other element, said head having a hole in its periphery which intersects a portion of the gear teeth, and a key insertible in said 55 hole and having teeth for engagement with the gear teeth.

In testimony whereof I have hereunto set my hand in the presence of two subscribing witnesses.

COLLINS K. ORTON.
